UNITED STATES PATENT OFFICE.

ALFRED E. WHITMORE, OF NORFOLK, VIRGINIA.

ADVERTISING DEVICE.

Application filed September 6, 1921. Serial No. 493,812.

To all whom it may concern:

Be it known that I, ALFRED E. WHITMORE, a citizen of the United States, residing at Norfolk, in the county of Norfolk and State of Virginia, have invented new and useful Improvements in Advertising Devices, of which the following is a specification.

This invention relates to an advertising device, the general object of the invention 10 being to provide a casing having a number of windows therein with means for successively moving a plurality of cards or plates bearing advertisements before said windows and holding them stationary for a 15 limited period.

Another object of the invention is to provide holding means for the cards or plates so formed that the cards or plates can be removed and new ones substituted whenever 20 desired.

A still further object of the invention is to provide means for displaying a number of sets of cards, one set being arranged on a rotary element and the other on an endless 25 belt, both the rotary element and the endless belt being driven from an electric motor.

This invention also consists in certain other features of construction and in the combination and arrangement of the several parts, to be hereinafter fully described, 30 illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a front view of a device constructed in accordance with my invention.

Figure 2 is a longitudinal sectional view.

Figure 3 is a section on line 3—3 of Figure 2.

Figure 4 is a section on line 4—4 of Figure 2.

Figures 5, 6 and 7 are detail views.

In these views 1 indicates a casing which is formed of any suitable material and is provided with suitable openings for providing access to the interior thereof. The upper part of the casing is of considerable less depth than the lower part and the front face of this lower part is connected with the front face of the upper part by a curved

wall 2. A window 3 is formed in the lower part of this curved wall and a window 4 is formed in the front face of the reduced upper part of the casing. The walls around the window 4 are made to imitate a stage of a theater, as shown at 5. Transparent plates 6 close the windows.

A shaft 7 is arranged in the lower part of the casing, under the curved wall, and a carrier frame 8 of octagon shape is rotatably mounted on said shaft. This frame includes the spokes 9 which have their inner ends connected with the hub 10 and their outer ends connected together by the pieces 11. The said pieces support clips or guides 12 for detachably receiving the cards or plates 13 upon which the advertising matter is placed. The parts are so proportioned that a card on the frame can be seen through the window 3 when the frame comes to rest with one of its sides adjacent the window. 75 A ratchet wheel 14 is secured to the hub of the frame and a dog 15 is slidably mounted in a bracket 16, arranged to engage said ratchet. A lever 17, pivoted intermediate its ends to a part of the casing, has one end pivoted to the outer end of the dog 15 and its other end adapted to be engaged by a dog 18 on a gear 19 which is mounted on a stub shaft 20 supported by a part of the casing. A train of gearing 21 connects this gear 19 with the shaft of an electric motor 22, located in the casing.

From the above it will be seen that at each revolution of gear 19 the tooth 18 will strike lever 17 and thus cause the dog 15 to slide forwardly and give the frame a partial rotation by means of the ratchet 14. This movement of the dog is sufficient to move one card away from the window and bring the next card into view through the window.

Four shafts 23 are arranged in the upper part of the casing and these shafts carry the feeding rollers 24 for the endless belt carrier 25. These shafts and rollers are so arranged as to cause the belt carrier to travel in a rectangular path. One of the shafts 23 is connected by shaft 26 and bevelled gears 27 with the rotary frame 9 so that the movement of this frame 9 will be imparted to the belt carrier. Card holders 28 have their upper ends hingedly connected with the belt carrier so that said holders re-

main in a vertical position at all times in the travel of the belt. These holders are provided with the guides 29 for detachably holding the cards 30 upon which the advertising matter is placed. As will be seen the cards carried by these holders will be brought before the window 4 in the travel of the belt carrier and as this carrier is actuated from the carrier 9 the card will remain stationary before the window during one rotation of the gear 19. When the carrier 9 is operated by the tooth 18 actuating the ratchet mechanism the old card will be withdrawn and a new card will take its place. Thus the advertising matter appearing at both windows will be changed after a limited time. Holders 31 may be placed on the front of the casing for holding stationary cards. The lamps 32 for lighting the cards carried by the holders 28 are arranged at the bottom, sides and top of the window 4 so as to make the lighting of the ads appearing at this window similar to that in a theater. The lamps 33 for illuminating the cards appearing at window 3 are arranged in the hollow hub of the carrier frame 9 and the cards 13 are made transparent so that the light will pass through these cards.

It will thus be seen that an attractive advertising device is provided which is simple in operation and can be manufactured to sell at low cost. The parts are so arranged that a plurality of advertisements can be brought into view at the windows and the cards are held stationary for a sufficient amount of time to permit a person to read the matter thereon.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

An advertising device of the character described comprising a casing having a reduced upper part and a rounded front face connecting the front face of the reduced part with the lower part, windows in the front face of the reduced part and the rounded part, lighting means arranged around the upper window, a movable element located adjacent each window, means for supporting advertising cards on said elements consisting of a shaft arranged in the lower part of the casing, a carrier frame of octagon shape rotatably mounted on said shaft, the frame including spokes having their inner ends connected to a hub and strips connecting the outer ends of said spokes together, said strips supporting guiding elements and cards containing advertising matter received in said guides, lamps for illuminating the cards appearing at the lower window, motor means for moving the movable elements thereby consisting of a train of gearing shafts, and an endless belt carrier which is designed to travel in a rectangular path.

In testimony whereof I affix my signature.

ALFRED E. WHITMORE.
